UNITED STATES PATENT OFFICE

2,082,119

MINING MACHINE

Thomas E. Pray, Chicago, Ill., assignor to Goodman Manufacturing Company, Chicago, Ill., a corporation of Illinois

Application April 19, 1933, Serial No. 666,838
Renewed October 1, 1936

12 Claims. (Cl. 262—28)

My invention relates to improvements in mining machines, and more particularly relates to improvements in a track-mounted mining machine adapted to cut and clean dirt bands from 5 coal seams.

My invention has as its principal objects to provide a new and improved mining machine of the class described, constructed with a view towards utmost efficiency and adaptability to 10 varying mining conditions together with a means whereby a complete stratum of dirt in the coal seam may be cleaned therefrom in one operation.

A prior application filed by William T. McCullough, on May 24, 1930, Serial No. 455,218, now Patent No. 1,943,832, shows a machine of the general class disclosed by my present invention. My present invention, however, is an improvement on the prior McCullough application in that 20 new and improved means are provided for collecting and conveying the cuttings away from the machine, and in that the machine of my present invention may completely cut out a dirt band from the coal seam and separate the dirt 25 from the coal in one continuous operation.

Other objects of my invention will appear from time to time as the following specification proceeds.

My invention may be more clearly understood 30 with reference to the accompanying drawings wherein:

Figure 1 is a top plan view of a device constructed in accordance with my invention with certain parts broken away and in section to more 35 clearly show the details thereof;

Figure 2 is an enlarged plan view of the forward portion of the device shown in Figure 1 with certain parts broken away and shown in horizontal section;

Figure 3 is an enlarged side elevation of the device shown in Figure 1 with certain parts broken away and shown in substantially longitudinal section;

Figure 4 is an enlarged sectional view taken 40 substantially along line 4—4 of Figure 2;

Figure 5 is an enlarged sectional view taken substantially along line 5—5 of Figure 2;

Figure 6 is an enlarged detail view of the truck 45 frame with parts broken away and in section;

Figure 7 is an enlarged sectional view taken substantially along line 7—7 of Figure 6;

Figure 8 is an enlarged detail view with parts broken away and in section showing details of the 50 cuttings-collecting mechanism in plan;

Figure 9 is a sectional view taken substantially along line 9—9 of Figure 2;

Figure 10 is an enlarged detail sectional view taken substantially along line 10—10 of Figure 1; and

Figure 11 is a sectional view taken substantially along line 11—11 of Figure 10.

Like numerals refer to like parts throughout the various figures.

In the drawings, the machine generally comprises a wheeled truck 10 adapted to travel on tracks laid on the mine floor. Mounted on the truck 10 is a turntable 11 having a pair of upright frame members 12, 12 spaced apart and supporting between them a cutting element 13 extending forwardly and rearwardly of the supporting frame members 12, 12 and including a main frame 14, a motor 15 secured to and extending rearwardly of said main frame, and a pair of parallel spaced horizontally disposed cutter bars 16 and 17 extending forwardly of said main frame.

The entire cutting element 13 is capable of being raised and lowered bodily by gear members 18, 18 on shafts 19, 19 engaging vertical racks 20, 20 carried by the supporting frames 12, 12. The shafts 19, 19 and gear members 18, 18 are driven from the motor 15 through a suitable system of reduction gearing in a manner which will hereinafter be more fully described.

The wheeled truck 10 includes a truck frame 21 carried by a rearward axle 22 having track wheels 23, 23 thereon. The rearward axle 22 is herein preferably shown as being rigidly journaled in the truck frame 21 so as to be incapable of axial movement with respect thereto. The forward portion of the truck frame 21 is supported on a floating axle 24 having track wheels 25, 25 thereon, which floating axle is so arranged as to be axially movable with respect to said truck frame to compensate for irregularities in the mine track and to permit vertical adjustment of the truck frame 21 with respect thereto for adjusting the angle of the cutter bars 16 and 17 with respect to the coal face to permit said cutter bars to cut a horizontal kerf in the mine wall where the track is uneven, or to permit said cutter bars to readily follow a pitching seam.

With reference now in particular to the means for adjusting the angular position of the cutter bars 16 and 17 with respect to the mine bottom, and the means for equalizing the truck wheels for travel over uneven mine tracks, and one of the novel features of my invention, the forward truck axle 24 is journaled in a pair of fulcrumed levers 50

27, 27 adjacent its opposite ends, but herein preferably shown as being inwardly of the truck wheels 25, 25. The fulcrumed levers 27, 27 are pivoted adjacent their rearward ends on pivotal pins 28, 28 carried by suitable brackets 29, 29 secured to the truck frame 21 in a suitable manner. The axle 24 is journaled intermediate the ends of the fulcrumed levers 27, 27 and the free ends of said levers are adapted to slidably engage the under surface of one lever arm 30 of bell crank members 31, 31 (see Figs. 3, 5, 6, and 7). The bell crank members 31, 31 are pivotally supported on the truck frame 21 by means of pivot pins 33, 33 carried in brackets 34, 34 which brackets in turn are secured to the truck frame 21 in a suitable manner. Another lever arm 35, of each bell crank member 31, is forked and has a nut 36 trunnioned in the forked portion of said lever arm. The nuts 36, 36 are adapted to be threaded on opposite ends of a transversely extending rod 37 so that movement of one fulcrumed lever 27 in one direction will cause movement of the opposite fulcrumed lever 27 in an opposite direction to compensate for irregularities in the mine track.

The threads on the end of the transversely extending rod 37 are so cut that the bell crank members 31, 31 may move simultaneously towards or away from the longitudinal center line of the truck frame 21 depending upon the direction of rotation of the rod 37 for pivoting said bell crank members about their axis of pivotal connection to the truck frame 21 and pivoting said truck frame about the axis of the rearward truck axle 22 for raising or lowering the forward portion of said truck frame with respect to the axle 24 in an obvious manner.

The threaded rod 37 has universal couplings 39, 39 secured to its opposite ends in a suitable manner. Sleeves 40, 40 are carried on the outer ends of the universal couplings 39, 39 and have sliding and driving engagement with the universal couplings 39, 39. The sleeves 40, 40 have driving engagement with other universal couplings 41, 41, which couplings in turn have sockets 42, 42 formed integral therewith for receiving squared shafts 43, 43 carried in the truck frame 21 in a suitable manner so that the transversely extending rod 37 will be free to move transversely with respect to the truck frame 21 and so that rotation of either one of the squared shafts 43, 43 by means of a suitable hand lever will pivot the truck frame 21 about the rearward axle 22 and elevate or lower the forward ends of the cutter bars 16 and 17.

It may thus be seen that a new and improved equalizing means has been provided for permitting the mining machine to travel over relatively rough tracks without derailing, which means also acts as a means for adjusting the angle of the mining machine and cutting element with respect to the mine bottom for permitting said cutting element to cut where the tracks are irregular or where the bottom or coal seam is uneven and that said means is as effective for elevating the cutter bar where the track is uneven as where it is even.

The method of securing the cutter bars 16 and 17 to the main frame 14 is best shown in Figures 2, 3, and 4. The cutter bar 16 is adapted to rest on and be secured to the main frame 14 with its longitudinal center line substantially coincident with the longitudinal center line of said main frame. A spacing member 44 is adapted to rest on the upper side of the cutter bar 16, and the cutter bar 17 is adapted to rest on the upper side

of said spacing member. A shoe 45 is adapted to engage the upper side of the cutter bar 17 and suitable cap screws 46, 46 are adapted to extend through the shoe 45, cutter bar 17, spacing member 44, cutter bar 16, and be threaded in suitable lugs 47 extending upwardly from the main frame 14 for securing the cutter bars 16 and 17 to said main frame. Likewise, a shoe 48 is spaced rearwardly of the shoe 45 and cap screws 49, 49 pass therethrough and are threaded in suitable lugs formed integral with the main frame 14 to aid in holding the cutter bars 16 and 17 to said main frame. The apertures in the cutter bars 16 and 17, through which the cap screws 46, 46 and 49, 49 pass, are elongated to permit independent longitudinal adjustment of said cutter bars to take up on the cutter chains movable thereabout and compensate for wear of said cutter chains.

The spacing member 44 may be of any suitable dimensions according to the thickness of kerf it is desired to cut, but as herein shown said spacing member is of such proportions that the top bits of the cutter chain movable about the cutter bar 16 are substantially on a level with the bottom bits of the cutter chain movable about the cutter bar 17 so that the thickness of the kerf cut by said cutter bars is substantially equal to twice the thickness of kerf cut by an ordinary cutter bar. Where the dirt band is thicker or thinner, these cutter bars may be spaced farther apart or closer together in an obvious manner.

A vertical shaft 50 has a bevel gear 53 keyed to its lower end, the hub of which bevel gear is journaled in a member 51 secured to the main frame 14. The vertical shaft 50 extends upwardly through the member 51 and has a cap 54 formed integral with its upper end and extending outwardly therefrom. The outer portion of the cap 54 abuts and rests on a sleeve 55 journaled for rotation about the member 51 coaxial with the shaft 50 on suitable ball bearings. A cutter chain sprocket 56 is secured to the sleeve 55 adjacent the lower end thereof and meshes with and drives a cutter chain 57 about the cutter bar 16. A spacing member 58 is disposed above the cutter chain sprocket 56 and a cutter chain sprocket 59 is disposed above the spacing member 58 and secured to the sleeve 55 in a suitable manner. The cutter chain sprocket 59 is adapted to mesh with and drive a cutter chain 60 about the cutter bar 17.

A key piece 62 is secured to the cap 54 of the vertical shaft 50 for rotation therewith in a suitable manner and is adapted to engage suitable slots formed in the hub of the cutter chain sprocket 59 for driving said sprocket and the sleeve 55 and cutter chain drive sprocket 56 upon rotation of the vertical shaft 50.

The teeth of the cutter chain sprockets 56 and 59 are alternately arranged so that the blocks of the cutter chain 57 will be disposed between the blocks of the cutter chain 60 to permit more even spacing of the cutter bits and prevent interference between the extreme up bits of the cutter chain 57 and the extreme down bits of the cutter chain 60, especially when the cutter bars 16 and 17 are so spaced as to cut a kerf of less thickness than the thickness of kerf cut by the two cutter chains when one is disposed directly above the other. The spacing of the cutter chain sprockets 56 and 59 may readily be changed by substitution of a spacing member 58 and changing the sleeve 55 and vertical shaft 50 where necessary to compensate for various desired spacings of the cutter bars 16 and 17.

The bevel gear 53 meshes with and is driven from a bevel pinion 61 on a longitudinally extending shaft 63 disposed beneath said bevel gear. The longitudinally extending shaft 63 is journaled in the main frame 14 in a suitable manner and has a spur gear 64 keyed adjacent its rearward end which is meshed with and driven from an armature pinion 65 of the motor 15.

The longitudinally extending shaft 63 extends forwardly of the bevel pinion 61 beyond the bevel gear 53 and has a bevel pinion 66 keyed adjacent its forward end which is adapted to mesh with and drive oppositely facing bevel gears 67, 67 freely mounted on a transversely extending shaft 68. The bevel gears 67, 67 are so arranged that they may be selectively connected with the transversely extending shaft 68 for driving said shaft in opposite directions without reversal of the motor 15 by means of suitable friction clutch members, generally indicated by reference character 69. Worms 70, 70 are keyed adjacent the outer ends of the transversely extending shaft 68 and mesh with and drive worm gears 71, 71 secured to the forward ends of the longitudinally extending shafts 19, 19 for bodily moving the cutting element 13 with respect to the turntable 11. The worms 70, 70 and worm gears 71, 71 are of a usual self-locking type for holding the cutting element 13 in any desired position of adjustment with respect to the turntable 11.

Referring now to the apparatus for collecting the cuttings discharged by the cutter chains 57 and 60 and discharging said cuttings beyond the machine, the main frame 14 is provided with vertical side walls 72, 72, which side walls, together with the bottom of said main frame, form in effect channels between the sides of the cutter bars 16 and 17 and said main frame. An extensible chute 73, open at its top and forward end and extending along the sides and beneath the cutter bars 16 and 17, is carried by the main frame 14 for slidable movement with respect thereto for collecting the cuttings discharged by the cutter chains 57 and 60. The extensible chute 73 is provided with side walls 74, 74 which extend along the vertical side walls 72, 72 of the main frame 14. The ends of the side walls 74, 74 extend outwardly along the top portions of the vertical side walls 72, 72 and are turned under flanges 75, 75 formed integral with and extending outwardly from the tops of the vertical side walls 72, 72. The central portion of the bottom of the extensible chute 73 is cut away to a point adjacent the forward end thereof, and the bottom of said chute on each side of the cut-away portion is formed to substantially conform to the channeled portion of the main frame 14 and is provided with upwardly extending sides which include inwardly extending flanges 76, 76 adapted to rest on and slide along suitable shouldered portions formed on the main frame 14 beneath the cutter bar 16. Thus, a collecting chute is formed along each side of the cutter bars 16 and 17 for collecting the cuttings discharged which is as effective when the cutter bars are cutting in reverse directions as when cutting in one direction.

A channel 77 extends across the bottom of the forward portion of the extensible chute 73 and has a vertically extending guide and support member 78 secured thereto. The guide and support member 78 is adapted to ride in slots 79 formed in and extending longitudinally of the cutter bars 16 and 17. Suitable rollers 80, 80 are adapted to ride in the slots 79, 79 of the cutter

bars 16 and 17 and engage the sides thereof. Rollers 81, 81 are carried by the guide and support member 78 and are adapted to engage the top surface of the cutter bar 16 on each side of the slot 79. A pair of tension members, herein preferably shown as being tension springs 83, 83, are secured to the guide and support member 78 in a suitable manner and extend forwardly and downwardly therefrom and have their forward ends secured to a member 84 fixed in the slot 79 of the cutter bar 16, in a usual manner, adjacent the forward end thereof, for yieldably holding the extensible chute 73 in a forward position with respect to the cutter bars 16 and 17.

A deflecting plate 85 is secured to the forward portion of the extensible chute 73 on the upper side thereof by means of a pivotal pin 86 disposed adjacent the central portion of said chute. The deflecting plate 85 is carried for pivotal movement with respect to the extensible chute 73 about the axis of the pivotal pin 86 and extends forwardly of said extensible chute. Suitable slots 87, 87 are provided in each side of the extensible chute 73 to permit pivotal movement of the deflecting plate 85 with respect to said chute so said plate may engage the mine wall for guiding said chute for movement along a curvilinear or irregular mine wall.

The extensible chute 73 is provided with extensible sides 88, 88 having outwardly rounded forward ends disposed adjacent the forward end of the deflecting plate 85 for engagement with the mine wall. The extensible sides 88, 88 are carried on the inner sides of the side walls 74 of the extensible chute 73 for slidable movement with respect thereto in a suitable manner, and have plates 89, 89 extending laterally outwardly therefrom and secured thereto in a suitable manner. The plates 89, 89 are spaced above the deflecting plate 85 a slight distance 40 and are parallel with said deflecting plate. The plates 89, 89 are provided with laterally extending slots 90, 90 which are adapted to be engaged with pivotal pins 91, 91 carried adjacent opposite sides of the deflecting plate 85.

With reference in particular to Figure 8, it may be seen that when the deflecting plate 85 is pivoted in one direction or another that one extensible side 88 will move in one direction while the other extensible side will be moved in an opposite direction with said deflecting plate so that the advance side of said plate and the advance extensible side will be adjacent the face of the coal for following a curvilinear coal face and forming an effective means for collecting the cuttings discharged by the cutter chains 57 and 60.

Cuttings carried rearwardly along the extensible chute 73 by the cutter chains 57 and 60 are adapted to be discharged through openings 92 and 93 formed in the main frame 14 rearwardly of the cutter bars 16 and 17 on opposite sides of a housing for the longitudinally extending shaft 63 and the gearing associated therewith.

A discharge hopper 94 is secured to and depends from the main frame 14 beneath the openings 92 and 93 and is in alignment with a discharge hopper 95 secured to a bored portion of the turntable 11 adjacent the central portion thereof to permit the cuttings to be discharged therethrough on to a longitudinally extending conveyor 96, as is best shown in Figure 5.

The longitudinally extending conveyor 96 may be of any type, but is herein preferably shown as being a flight conveyor comprising a pair of endless chains 97 having flights 98 carried there-

between riding along and under a pan 99. The longitudinally extending conveyor 96 extends rearwardly from a position disposed forwardly of the forward end of the truck frame 21 along said 5 truck frame and angularly upwardly to an elevated position rearwardly of the rearward end of said truck frame and has an open forward end disposed forwardly of said truck frame to permit cuttings to be shoveled therein by hand during 10 the cleaning up operation. The longitudinally extending conveyor 96 may be driven in any suitable manner, but is herein preferably shown as being driven from a motor 100 on the truck frame 21 through a suitable system of reduction gearing 15 and chain and sprocket drives which is not herein shown in detail since it forms no portion of my present invention.

A discharge conveyor 101 is carried rearwardly of the truck frame 21 for pivotal movement with 20 respect thereto beneath the rearward end of the longitudinally extending conveyor 96 and is provided with a hopper 102 to catch material discharged by the longitudinally extending conveyor 96. The discharge conveyor 101 is of the endless 25 chain type and includes a pair of endless chains 103, 103 threaded around suitable sprockets in a usual manner and having flights 104 carried therebetween and riding over and under a bottom plate 105.

30 The discharge conveyor 101 is so arranged as to extend over a mine car for discharging material therein and is provided with a movable bottom plate 106 carried beneath the bottom plate 105 and extensible forwardly thereof. The movable bottom plate 106 is carried in suitable guides 107, 107 formed in inwardly projecting portions 108 of side members 109, 109 secured to inner sides of a frame member 110 for the discharge conveyor 101. A rack 111 is secured to and depends from the movable bottom plate 106 and extends longitudinally therealong adjacent the central portion thereof. The rack 111 is adapted to be engaged by a pinion 112 keyed on a transversely extending shaft 113 journaled in the 45 frame member 110 for the discharge conveyor 101. Suitable hand wheels 114 are provided on opposite ends of the transversely extending shaft 113 for rotating said shaft and longitudinally moving the movable bottom plate 106 with respect to the bottom plate 105. It is thus apparent that the discharge conveyor 101 is so arranged that the point at which material is to be discharged thereby may readily be controlled. Such an arrangement is particularly adapted for 55 loading and trimming cars inasmuch as one end of the car may be loaded and the movable bottom plate 106 may be moved with respect thereto for evenly loading the entire car and trimming the top surface thereof.

60 With reference now to a brief description of the use and operation of the device embodying my invention and my improved method of cleaning a dirt band from the coal seam, the cutter bars 16 and 17 are so spaced that the top and bottom bits may cut along the top and bottom of the dirt stratum. The dirt strata in one seam of coal are usually of the same thickness, and where the machine is cutting in other seams than the seam it was originally designed to cut, the 65 spacing of the cutter bars 16 and 17 may readily be changed to compensate for the increase or decrease in thickness of the dirt strata in a manner which has hereinbefore been described. The machine being adjacent the working place, the 70 cutter bars 16 and 17 may be dumped into the 75

dirt band by movement of the wheeled truck 10 along the mine bottom effected either by the truck wheels 23, 23 and 25, 25 driven from the motor 100 in the usual manner (not shown) or by means of a suitable rope feed in the usual 5 manner (not shown), the cutter bars 16 and 17 cutting in the dirt band and completely cutting cut said dirt band. As the cutter bars 16 and 17 are being dumped into the coal, the deflecting plate 85 and forward ends of the extensible 10 sides 88 will engage the coal face for collecting the cuttings as they are discharged by the cutter chains 57 and 60. The cuttings so collected will be carried by said cutter chains along the extensible chute 73 through the openings 92 and 15 93 and the main frame 14 and through the center of the turntable 11 to the longitudinally extending conveyor 96 from where they in turn will be discharged away from the machine. After the cutter bars 16 and 17 have been completely 20 dumped into the coal, said cutter bars may be fed across the coal face by the turntable 11 and then withdrawn therefrom in the usual manner, it being understood that the deflecting plate 85 is adjacent the face of the coal during the entire 25 cutting operation and that the dirt cut out by said cutter bars is continuously cleaned from the coal face and deposited in a place remote therefrom except during the initial dumping operation and the latter part of the withdrawing 30 operation when cuttings falling on the floor may be shoveled into the open forward end of the conveyor 88.

It may thus be seen that the device of my invention effects the cleaning of the coal at the 35 face by completely cutting out and cleaning the dirt therefrom, which in turn is collected and removed from the coal face during the cutting operation, thus eliminating the necessity for picking and cleaning the coal outside of the mine. 40

While I have herein shown and described one form of my invention, it will be understood that the construction and arrangement of the various parts may be altered without departing from the spirit and scope thereof. Furthermore, I do not 45 wish to be construed as limiting myself to the specific form illustrated, excepting as it may be specifically limited in the appended claims.

I claim as my invention:

1. In a mining machine, a truck, a turntable 50 thereon, a discharge opening in said turntable, a cutting element on said turntable including a motor arranged rearwardly of said discharge opening, a frame extending forwardly from said motor over said discharge opening, a cutter chain 55 carrying cutter bar projecting from said frame arranged so that its rearward end is forwardly of said discharge opening in said turntable and adapted to cut a horizontal kerf, and an opening in said frame rearwardly of said cutter bar 60 and forwardly of the forward end of said motor, disposed directly above and communicating with said discharge opening in said turntable.

2. In a mining machine, a truck, a conveyer on 65 said truck, a turntable on said truck, a cutting element on said turntable including a frame, a motor disposed rearwardly of said frame for movement therewith, and cutting mechanism projecting forwardly of said frame including a cutter bar having a cutter chain movable thereabout, a sprocket disposed rearwardly of said cutter bar and spaced forwardly of said motor for driving said cutter chain about said cutter bar, a drive connection from said motor to said 70 sprocket including a longitudinal shaft driven 75

by said motor and disposed beneath said sprocket and cutter bar, a portion of said frame forming a housing for said shaft and said frame being open on each side of said housing for the discharge of cuttings therethrough onto said conveyer.

3. In a mining machine, a truck, a conveyer on said truck, a turntable on said truck above said conveyer, a discharge opening in said turntable, 10 a cutting element supported on said turntable including a frame, a motor disposed rearwardly of said frame and discharge opening and mounted thereon for bodily movement therewith, a forwardly projecting cutter bar supported on 15 said frame forwardly of said discharge opening, a cutter chain drive sprocket disposed forwardly of said discharge opening, and a cutter chain driven about said cutter bar by said sprocket, a drive connection from said motor to said sprocket including a longitudinal shaft supported in 20 said frame beneath said sprocket and cutter bar, a frame beneath said sprocket and cutter bar, a portion of said frame forming a housing for said shaft and said frame being open on each side of said housing in alignment with said discharge opening in said turntable for the 25 discharge of cuttings onto said conveyer.

4. In a mining machine, a truck, a cutting element on said truck including a frame, a motor disposed rearwardly of said frame for movement therewith, and cutting mechanism projecting forwardly of said frame including a cutter bar having a cutter chain movable thereabout, a sprocket disposed forwardly of said motor for driving said cutter chain about said cutter bar, a drive connection from said motor to said sprocket, said frame having a channel formed therein on the advance side of said cutter bar and leading rearwardly therealong and extending upwardly along the sides of said cutter bar, said 35 channel leading into a hopper formed in said frame disposed between said cutter bar and motor, and said hopper having a discharge opening in the bottom thereof on the advance side of said cutter bar in alignment with said channel.

45 5. In a mining machine, a truck, a cutting element on said truck including a frame, a motor disposed rearwardly of said frame for movement therewith, and cutting mechanism projecting forwardly of said frame including a cutter bar having a cutter chain movable thereabout, a sprocket disposed rearwardly of said cutter bar and spaced forwardly of said motor for driving said cutter chain about said cutter bar, a drive connection from said motor to said 50 sprocket including a longitudinal shaft driven by said motor and disposed beneath said sprocket and cutter bar, said frame having a channel formed therein on each side of said cutter bar and leading rearwardly therealong and extending upwardly along the sides of said cutter bar, said channels leading into a hopper formed in said frame disposed between said cutter bar and motor, and said hopper having openings on opposite sides of said shaft in alignment with said 55 channels.

6. In a mining machine, a truck, a cutting element on said truck including a frame, a motor disposed rearwardly of said frame for movement therewith, and cutting mechanism projecting forwardly of said frame including a cutter bar having a cutter chain movable thereabout, a sprocket disposed rearwardly of said cutter bar and spaced forwardly of said motor for driving said cutter chain about said cutter 70 bar, a drive connection from said motor to said

sprocket including a longitudinal shaft driven by said motor and disposed beneath said sprocket and cutter bar, said frame having a channel formed therein on each side of said cutter bar and leading rearwardly therealong, and openings 5 in said frame disposed beneath and leading from said channels and disposed rearwardly of said sprocket and forwardly of said motor on opposite sides of said shaft for the discharge of cuttings therethrough propelled along one of said 10 channels by said cutter chain.

7. In a mining machine, a truck, a turntable thereon, a discharge opening in said turntable, a cutting element supported on said turntable including a frame, a motor disposed rearwardly 15 of said frame and discharge opening and mounted thereon for bodily movement therewith, a forwardly projecting cutter bar supported on said frame forwardly of said discharge opening, a cutter chain drive sprocket disposed forwardly of said discharge opening, and a cutter chain driven about said cutter bar by said sprocket, a drive connection from said motor to said sprocket including a longitudinal shaft supported in 20 said frame beneath said sprocket and cutter bar, said frame having a channel formed on the advance side of said cutter bar leading rearwardly along said cutter bar beyond the rearward end thereof, an opening in said frame on the advance 25 side of said shaft and disposed beneath and leading from said channel, said opening being in alignment with and communicating with said discharge opening in said turntable for the discharge of cuttings therethrough propelled along 30 said channel by said cutter chain.

8. In a mining machine, a truck, a turntable thereon, a discharge opening in said turntable, a cutting element supported on said turntable including a frame, a motor disposed rearwardly 35 of said frame and discharge opening and mounted thereon for bodily movement therewith, a forwardly projecting cutter bar supported on said frame forwardly of said discharge opening, a cutter chain drive sprocket disposed forwardly of said discharge opening, and a cutter chain driven about said cutter bar by said sprocket, a drive connection from said motor to said sprocket including a longitudinal shaft supported in 40 said frame beneath said sprocket and cutter bar, means associated with said cutter bar for collecting the cuttings discharged thereby and directing them to a point rearwardly of said cutter chain sprocket including a channel formed in said frame on each side of said cutter bar and leading rearwardly from said cutter 45 bar, and openings in said frame leading from said channels and disposed rearwardly of said sprocket and on opposite sides of said shaft in alignment with and communicating with said discharge opening in said turntable for the discharge of cuttings therethrough propelled along 50 one of said channels by said cutter chain.

9. In a mining machine, a truck, a turntable thereon, a cutting element supported on said turntable for vertical adjustment with respect thereto, a frame, a motor disposed rearwardly of and supported by said frame for bodily movement therewith, and cutting mechanism supported by and projecting forwardly of said frame including a cutter bar having a cutter chain movable thereabout, a sprocket disposed rearwardly of said cutter bar and forwardly of said motor for driving said cutter chain about said cutter bar, elevating mechanism on said frame disposed forwardly of said cutter chain sprocket 70

for vertically adjusting the cutting position of said cutter bar, means driven by the forward end of said motor for driving said cutter chain about said cutter bar and selectively driving said 5 elevating mechanism including a shaft extending longitudinally forwardly of said motor along said frame forwardly of said cutter chain sprocket, a drive connection from the forward end of said shaft to said elevating mechanism 10 and a drive connection from an intermediate portion of said shaft to said cutter chain drive sprocket, a portion of said frame forming a housing for said shaft and said frame being open on each side of said shaft forwardly of 15 said motor and rearwardly of said sprocket to permit the discharge of cuttings therethrough.

10. In a mining machine, a truck, a conveyer extending along said truck, a turntable on said truck, a discharge opening in said turntable above said conveyer, cutting mechanism on said turntable including a motor, a frame extending forwardly therefrom, a pair of parallel-spaced cutter bars projecting from said frame and spaced in such relation with respect to each 20 other as to cut adjacent the top and bottom of a dirt band in a coal seam and adapted to completely cut out a dirt band in the coal seam by simultaneous lateral swinging movement across the front of said truck or by bodily movement of the machine, means cooperating with 25 said cutter bars for collecting the cuttings discharged thereby and directing them to a point disposed rearwardly thereof including a channel formed on the advance side of said cutter bars and leading to an opening in said frame 30 communicating with said discharge opening in said turntable for the discharge of cuttings therethrough on to said conveyer.

11. In a mining machine, a truck, a conveyer 40 on said truck extending therealong and rearwardly thereof, a turntable on said truck, a discharge opening in said turntable above said conveyer, a cutting element on said turntable adapted to completely cut out and clean a dirt 45 band in a coal seam in a continuous operation including a motor, a frame secured thereto and extending forwardly therefrom above said dis-

charge opening, a pair of parallel-spaced projecting cutter bars spaced in such relation with respect to each other as to cut adjacent the top and bottom of a dirt band in a coal seam and adapted to completely cut out a dirt band in 5 the coal seam by simultaneous lateral swinging movement across the front of said truck or by movement of the machine along a track, means cooperating with said cutter bars for collecting the cuttings discharged thereby and directing 10 them to a point disposed rearwardly thereof, and openings in said frame on each side thereof disposed above and communicating with said discharge opening in said turntable for discharging the cuttings therethrough onto said 15 conveyer.

12. In a mining machine, a truck, a conveyer on said truck extending therealong and rearwardly thereof, a turntable on said truck, a discharge opening in said turntable above said 20 conveyer, a cutting element on said turntable adapted to completely cut out and clean a dirt band in a coal seam in a continuous operation including a motor, a frame secured thereto and extending forwardly therefrom above said discharge opening, a pair of parallel-spaced projecting cutter bars having cutter chains movable thereabout spaced in such relation with respect to each other as to cut adjacent the top and bottom of a dirt band in a coal seam and 25 adapted to completely cut out a dirt band in the coal seam by simultaneous lateral swinging movement across the front of said truck or by movement of the machine along a track, means cooperating with said cutter bars for collecting 30 the cuttings discharged thereby and directing them to a point disposed rearwardly therefrom, means driven by said motor for driving said cutter chain about said cutter bar including a shaft 35 extending longitudinally forwardly thereof over said discharge opening in said turntable, and openings in said frame on each side of said shaft disposed above and communicating with said discharge opening in said turntable for discharging the cuttings therethrough onto said 40 conveyer.

THOMAS E. PRAY.
